US0D1112512S

(12) **United States Design Patent** (10) Patent No.: **US D1,112,512 S**
(45) Date of Patent: ** Feb. 10, 2026

(54) **FIDGET TOY**

(71) Applicant: **Zhenbang Liu**, Dongguan (CN)

(72) Inventor: **Zhenbang Liu**, Dongguan (CN)

(73) Assignee: **Zhenbang Liu**, Guangdong (CN)

(*) Notice: Patent file contains an affidavit/declaration under 37 CFR 1.130(b).

(**) Term: **15 Years**

(21) Appl. No.: **35/522,622**

(22) Filed: **Sep. 24, 2024**

(80) **Hague Agreement Data**

Int. Filing Date: **Sep. 24, 2024**

Int. Reg. No.: **DM/240622**

Int. Reg. Date: **Sep. 24, 2024**

Int. Reg. Pub. Date: **Oct. 11, 2024**

(51) **LOC (15) Cl.** 21-01

(52) **U.S. Cl.**

USPC **D21/407**

(58) **Field of Classification Search**
